UNITED STATES PATENT OFFICE

157,856

COMBINED TOOL CABINET AND WORKBENCH

Alexander P. Fox, University City, and August D. Reisert, St. Louis, Mo., assignors to Lincoln Engineering Company, St. Louis, Mo., a corporation of Missouri

Application December 18, 1948, Serial No. 150,236

Term of patent 7 years

(Cl. D33—19)

To all whom it may concern:

Be it known that we, Alexander P. Fox and August D. Reisert, citizens of the United States and residents of University City, St. Louis County, Missouri, and St. Louis, Missouri, respectively, have invented a new, original, and ornamental Design for Combined Tool Cabinet and Workbench, of which the following is a specification, reference being had to the accompanying drawing forming part thereof, in which:

Fig. 1 is a trimetric view showing my new design;

Fig. 2 is a plan view;
Fig. 3 is a front elevation;
Fig. 4 is a left-end view of Fig. 3;
Fig. 5 is a right-end view of Fig. 3; and,
Fig. 6 is a rear elevation.

We claim:
The ornamental design for a combined tool cabinet and workbench, substantially as shown.

ALEXANDER P. FOX.
AUGUST D. REISERT.
